No. 895,016.

PATENTED AUG. 4, 1908.

C. J. HERRMANN.
PORTABLE PIE CRATE.
APPLICATION FILED DEC. 10, 1907.

UNITED STATES PATENT OFFICE.

CARL J. HERRMANN, OF BROOKLYN, NEW YORK.

PORTABLE PIE-CRATE.

No. 895,016.

Specification of Letters Patent.

Patented Aug. 4, 1908.

Application filed December 10, 1907. Serial No. 405,838.

To all whom it may concern:

Be it known that I, CARL J. HERRMANN, a citizen of the United States, and residing at Brooklyn, in the county of Kings and State 5 of New York, have invented certain new and useful Improvements in Portable Pie-Crates, of which the following is a specification, such as will enable those skilled in the art to which it appertains to make and use the 10 same.

This invention relates to crates and similar devices for use by bakers in packing and carrying pies for delivery to customers; and the object of the invention is to provide an 15 improved device of this class, and which also may be used for packing and delivering other articles of food placed on plates or pans; a further object being to provide a 20 crate of the class specified into which plates or pans may be conveniently inserted and securely held against movement and easily and conveniently removed from the crate whenever desired.

The invention is an improvement on that 25 described and claimed in United States Letters Patent, granted to me Sept. 24, 1907, #866,860, and is fully disclosed in the following specification, of which the accompanying drawing forms a part, in which the separate 30 parts of my improvement are designated by suitable reference characters in each of the views, and in which;—

Figure 1 is a plan view of my improved 35 crate, part of the construction being in section, Fig. 2 a section on the line 2—2 of Fig. 1, Fig. 3 a perspective view of a detail of the construction, and;—Fig. 4 a plan view of a modified form of another detail of the construction shown in Fig. 1.

40 In the practice of my invention I provide a plurality of uprights or posts, which are preferably three in number and which are designated in the drawing by the reference characters a , a^2 and a^3 , and these uprights 45 or posts are placed in the form of a semi-circle, and connected therewith are a plurality of semi-circular supports b which constitute semi-circular shelves.

In the construction shown in Figs. 1 and 2, 50 the supports b are composed of a strong wire or rod bent into semi-circular form, and are connected with the uprights or posts a , a^2 and a^3 by means of radially and inwardly directed arms or brackets c through which 55 they are passed, but this connection of the

supports b with the uprights or posts a , a^2 and a^3 may be made in any desired manner, all that is necessary in this connection being that said supports be set inwardly a predetermined distance from said uprights or 60 posts, and in practice the said supports are preferably inclined slightly downwardly and backwardly as clearly indicated in Fig. 2. I also provide a supplemental upright or post a^4 which is connected with the upright 65 or post a , and by means of tubes d and which is placed directly in front of the said upright or post a , and in the outer or front ends of the tubes d , two of which are shown, but any desired number of which may be employed. 70 are placed spring operated plugs e between which, and the inner ends of the tubes d are placed strong spiral springs f . I also provide a locking device g consisting, in the form of construction shown, of an upright 75 plate or bar g^2 having laterally directed arms g^3 provided with heads g^4 which are approximately circular in form, and the heads g^4 , in the form of construction shown, are provided with ratchet teeth g^5 forming 80 corresponding recesses g^6 .

The tubes d project through the upright or post a^4 and are provided with jaws d^2 between which the heads g^4 of the arms g^3 are pivoted as clearly shown at h in Fig. 1, and 85 the upright plate or bar g^2 of the locking device g is provided transversely of its inner face with spaced teeth or projections g^7 forming corresponding recesses g^8 .

The outer end of the spring operating plugs 90 e is V-shaped in form and adapted to enter the recesses g^6 in the heads g^4 of the arms g^3 of the locking device g , and said plugs are designed to hold the locking device in closed and operative position as shown in full lines 95 in Fig. 1, or in different open positions as indicated in dotted lines in said figure.

In practice plates or pans i indicated in dotted lines in Figs. 1 and 2 are inserted into the crate and rest on the sides b , and when in 100 position in the crate said plates or pans project forwardly of the uprights or posts a , a^2 and a^3 , as is also clearly shown in Figs. 1 and 2, and when said plates or pans have been placed in position in the crate, the locking 105 device g is swung into the position shown in full lines in Figs. 1 and 2 and the front edges of the plates or pans i enter the recesses g^8 and said plates or pans are fully supported and also locked in the crate until the locking 110

device *g* is swung outwardly as indicated in dotted lines in Fig. 1, after which the plates or pans *i* may be removed from the crate.

In Fig. 4 I have shown at *b*² a modified form of the supports *b* which constitute the semi-circular shelves, and on which the plates or pans are placed, and which consists of a semi-circular plate, the inner edge of which is inclined downwardly, and said plate is riveted to bracket arms *c*³ which may be secured to the uprights or posts *a*, *a*² and *a*³ in any desired manner.

My invention is not limited to the exact form of locking device *g* shown in the drawing, and it will be seen that this locking device constitutes a form of door which partially closes the front of the crate and any construction of a device of the same general form that will operate in a similar manner may be employed. My invention is also not limited to the teeth *g*⁵ on the heads *g*⁴ of the arms *g*³ of the locking device, and the corresponding recesses *g*⁶, nor to providing the brackets *e* with V-shaped ends, as various other forms of construction may be employed for holding the locking device *g* in different positions.

Having fully described my invention, what I claim as new and desire to secure by Letters Patent, is:—

1. A crate of the class described, comprising a plurality of uprights placed in a semi-circular position, and two of which are opposite each other, semi-circular supports connected with said uprights and set inwardly therefrom, a supplemental upright placed in front of one of the opposite uprights and connected therewith by tubes in which are placed spring operated plugs, and a locking device provided with head members pivoted at the ends of said tubes and in connection with which said plugs operate, and by which said locking device may be held in different positions, said locking device being adapted to bear on the edges of plates or pans placed on said supports.

2. A crate of the class described, comprising a plurality of uprights placed in a semi-circular position, and two of which are opposite each other, semi-circular supports connected with said uprights and set inwardly therefrom, a supplemental upright placed in front of one of the opposite uprights and connected therewith by tubes in which are placed spring operated plugs, and a locking device provided with head members pivoted at the ends of said tubes and in connection with which said plugs operate, and by which

said locking device may be held in different positions, said locking device being adapted to bear on the edges of plates or pans placed on said supports, and being provided with transverse recesses adapted to receive said edges.

3. A crate of the class described, comprising a plurality of uprights placed in a semi-circular position and two of which are opposite each other, semi-circular supports connected with said uprights inwardly thereof, a supplemental upright arranged forwardly of one of the opposite uprights and connected therewith and provided with tubes in which are placed spring operated plugs, a locking device provided with members hinged at the ends of said tubes, and in connection with which said plugs operate, said plugs being adapted to hold said locking device in different positions.

4. A crate of the class described, comprising a plurality of uprights placed in a semi-circular position and two of which are opposite each other, semi-circular supports connected with said uprights inwardly thereof, a supplemental upright arranged forwardly of one of the opposite uprights and connected therewith and provided with tubes in which are placed spring operated plugs, a locking device provided with members hinged at the ends of said tubes, and in connection with which said plugs operate, said plugs being adapted to hold said locking device in different position, and said locking device being adapted to bear on the front edges of plates or pans placed in the crate.

5. A crate of the class described, comprising a plurality of uprights placed in a semi-circular position, semi-circular supports connected with the inner sides of said uprights, and a locking device hinged to one of the end uprights and adapted to bear on plates or pans placed on said supports, the hinged members of said locking device being provided, one with a head having notches or recesses therein, and the other with a spring operated plug adapted to enter said notches or recesses, whereby it may be held in a variety of positions.

In testimony that I claim the foregoing as my invention I have signed my name in presence of the subscribing witnesses this 7th day of December 1907.

CARL J. HERRMANN.
